EDWIN S. WEROLIN, OF BROOKLYN, NEW YORK, ASSIGNOR TO SOHMER & COMPANY, OF NEW YORK, N. Y.

VACUUM-CONTROLLING DEVICE FOR PLAYER-PIANOS.

1,169,896.

Specification of Letters Patent.

Patented Feb. 1, 1916.

Application filed April 7, 1915. Serial No. 19,785.

To all whom it may concern:

Be it known that I, EDWIN S. WEROLIN, a citizen of the United States, and a resident of Brooklyn, in the county of Kings and State of New York, have invented certain new and useful Improvements in Vacuum-Controlling Devices for Player-Pianos, of which the following is a specification.

This invention relates to novel and efficient means for automatically regulating the suction in the pneumatics of a player piano and checking any undue influence of the pump bellows on the same so that in this way the action is caused to express accurately, the forte or piano effects desired by the operator.

In the accompanying drawing: Figure 1 is a longitudinal section partly in side view of a vacuum controlling device embodying my invention, showing the pneumatic collapsed; Fig. 2 a similar section through the lower part of the device, showing the pneumatic expanded; Fig. 3 a plan partly in section of Fig. 2, and Fig. 4 a cross section of the end of the vacuum chamber, showing its connection with the suction pipe.

The device consists essentially of an elbow pipe 1, leading from the equalizing bellows of a pump (not shown) to the gate box 2 which communicates by suction pipe 3, with the vacuum chambers 4 of the pneumatics as usual. During playing the suction produced by the pump will cause a corresponding suction to be created in chamber 4, which by the action of the usual valves actuates the hammer in the usual manner. If it is desired by the operator to change from loud to soft, he will accordingly slow up on the pump. But inasmuch as there still exists a high suction in the pump bellows, the valves will be at first still under the influence of this high suction, so that a quick response of the action is not obtained. To obviate this defect I have devised the following construction: To one of the boards of gate box 2 there is affixed a small pneumatic 5 which communicates with the interior of the box by means of an air duct 6. From the movable member 7 of the pneumatic projects an arm 8 which by rod 9, is connected to a cranked spindle 10 passing diametrically through pipe 3. Spindle 10 carries a disk valve 11 which in its vertical position leaves pipe 3 unobstructed, while it closes the pipe when swung across the same. The throw

of rod 9 is checked by means of a pair of pins 12, extending laterally therefrom, and adapted to engage a stop 13 that projects upwardly from the fixed member 14 of pneumatic 5. The position of valve 11 may be ascertained by means of a pointer 15, likewise extending upwardly from member 14 and coöperating with a scale 16 formed on rod 9.

Pneumatic 5, is influenced by a spring 17, secured at one of its ends to movable member 7, while its other apertured end embraces a second screw rod 18 depending from box 2. A regulating button 19 carrying a washer 20 and mounted upon rod 18, so as to form a seat for spring 17, permits the tension of the latter to be adjusted. When during forte playing suction is created in the pump bellows, the resulting suction in the gate box, will by duct 6, exhaust pneumatic 5 and thus collapse the same against action of spring 17. In this way valve 11 will be opened (Fig. 1) and a correspondingly high suction will be formed in the vacuum chamber 4, so as to operate the action with full force. If now the tone is to be lowered more or less, suction in the pump bellows is reduced and consequently the suction in box 2 is also reduced to such an extent as to permit spring 17 to expand pneumatic 5 and thus throw valve 11 more or less across pipe 3 (Fig. 2). The valve will by being thus automatically interposed between the vacuum chamber 4 and the pump bellows, serve to check the undue influence of any excessive suction present in said bellows from acting on the valves and hammers of the action. If the action of the pump be again increased, the vacuum in box 2 will be correspondingly increased, so that the valve 11 will again open and place the action under stronger suction.

It will be seen that by my invention a quick response of the action is obtained so that any interpretation desired by the player will be promptly carried into effect.

I claim:

1. A device of the character described, comprising a pipe adapted to be placed under variable suction, a pneumatic communicating with said pipe and adapted to be automatically expanded or contracted upon a decrease or increase of said suction, a valve controlling the pipe, means for opening the valve on a contraction of the bellows

and for closing the valve on an expansion of the bellows, and a vacuum chamber of a self-player action communicating with the pipe.

- 5 2. A device of the character described, comprising a pipe adapted to be placed under variable suction, a gate box communicating with the pipe and adapted to be placed under corresponding variable suction, a pneumatic communicating with the pipe through said gate box and adapted to be automatically expanded or contracted upon a decrease or increase of said suction, a valve controlling the pipe, means for opening the valve on a contraction of the bellows and for closing the valve on an expansion of the bellows, and a vacuum chamber of a self-player action communicating with the pipe.
- 10 15 3. A device of the character described, comprising a pipe adapted to be placed under variable suction, a pneumatic communicating with said pipe and adapted to be automatically expanded or contracted upon a decrease or increase of said suction, a cranked spindle passing diametrically through the pipe, a valve mounted on said spindle, means for operably securing the pneumatic to the spindle, and a vacuum chamber of a self-player action communicating with the pipe.
- 20

be automatically expanded or contracted upon a decrease or increase of said suction, a spring secured to the movable member of the pneumatic, means for regulating the tension of said spring, a valve controlling the pipe, means for opening the valve on a contraction of the bellows and for closing the valve on an expansion of the bellows, and a vacuum chamber of a self-player action communicating with the pipe.

4. A device of the character described, comprising a pipe adapted to be placed under variable suction, a pneumatic communicating with said pipe and adapted to be automatically expanded or contracted upon a decrease or increase of said suction, a cranked spindle passing diametrically through the pipe, a valve mounted on said spindle, means for operably securing the pneumatic to the spindle, and a vacuum chamber of a self-player action communicating with the pipe.

EDWIN S. WEROLIN.
